6271X

Blake & Cushing,

Wrench.

Patented Dec. 14, 1830.

The improved Bed Key is a substitute for the common Bed Key and is made of the following or similarly appropriate substance, form and dimensions: Fig. The material or substance of which the improved Bed Key is made is cast iron, but Brass, Copper or the like may be substituted. The form is somewhat changed in different keys according to the number of arms of Bed Staves, which the keys adaptively are calculated to fit. But a fully made key consists of a central rod, four arms or shafts extending from the central right angles and in the same line with each other. The centre is flat and each arm or shaft is round and has a square opening in the vicinity of its being a socket for the reception of the head of the screw. The general dimensions of the improved Bed Key will admit of much variation. A convenient size however may be as follows: Fig. The center being one and a half inch in diameter and one inch thick, each arm being four inches long and one inch in diameter. The openings or sockets half an inch square and some of them more and some of them less. each opening or socket differing in size from any other in the same key. The number of arms is not confined to four, but may be one, two, three, four or more at pleasure. A square hole is made through the centre from side to side of a different size from any of the arms, and this adds to the number of sockets. or the centre may be oblong instead of circular having several square holes through it to accommodate various different sizes. - This little instrument is to be cast after first having the several recesses of varying sizes made and copper wire wound around it, so that it is the same as that of using the common

Bed Key. 2nd May. The unpermeability of the impervious cover this summer
had the effect of impounding a series of greater number of pools and
of its being made of such materials and in such a manner as to last
less than the key river in size
